WALTER FERRIS, OF SOUTH MILWAUKEE, WISCONSIN, ASSIGNOR TO BUCYRUS COMPANY, OF SOUTH MILWAUKEE, WISCONSIN, A CORPORATION OF WISCONSIN.

CAR AND PLATFORM FOR LOCOMOTIVE-CRANES AND THE LIKE.

1,358,835.

Specification of Letters Patent. Patented Nov. 16, 1920.

Application filed March 1, 1917. Serial No. 151,858.

To all whom it may concern:

Be it known that I, WALTER FERRIS, a citizen of the United States, residing at South Milwaukee, in the county of Milwaukee and State of Wisconsin, have invented a certain new and useful Improvement in Cars and Platforms for Locomotive-Cranes and the like, of which the following is a specification.

- 10 My invention relates to improvements in a car and platform and associated parts for locomotive cranes and the like. The invention embraces generally speaking, the subject matter of the running gear, the supporting gear, the turn table, the platform rotatably mounted on the turn table, and the means for fastening said parts together for mutually associating them and the relative arrangements of the different parts and their supporting, adjusting and coöoperating features. Generally speaking, the objects of my invention are to provide a new and improved car body construction which consists essentially of a large steel center casting to which the side girders are attached by means of rivets and bolts. Heavy cross girders connect the said girders at the two ends of the car frame, and are provided with suitable frames or guides in which the outriggers slide. Cross girders over the trucks are fitted with center bearings. The large center casting by its use, permits the construction of a very greatly simplified and strengthened car body and aids greatly to the ease and cheapness of construction in that by this arrangement it is only necessary to fabricate completely the side girders and then assemble them with the casting in the car itself.
- 40 The center casting combines in one unit the car separators and rolling tracks without interfering with provision for mounting and swinging the rack. The parts are so arranged that at the forward or jib end of the revolving frame which rides on the track carried by the casting the rollers supporting the frame are in contact with the roller track which track it will be understood, is formed on the web of the swinging rack mounted on the casting. The rollers at the rear or boiler end of the revolving frame travel between contact surfaces inside the casting, the arrangement of the parts being such that as the crane lifts 50 a load the downward reaction at the forward
- end is taken by the upper roller track. The resulting upward reaction at the boiler end is taken by the upper side of the lower roller track within the casting so that by this arrangement there is no necessity for a king pin or bolt passing between the center of the rotation, because the rearmost rollers carry the upward load. Thus this upward load is carried through a long lever arm and friction and the strain upon the parts are both greatly reduced. When the revolving frame is rotated without carrying a load on the job the rear rollers exert a downward pressure on the end side of the roller track. Since these three tracks, the two inside the casting, and the one on top of it, are complete circles, the crane which may be rotated at an angle of 360° can do its work at any point.
- 60 It will be understood that the upper roller track is embodied in a separate rack casting which is rigidly held by bolts or rivets on the upper surface of the casting. This is desirable for two reasons, first, in order that the swinging gear may be replaced when the gear teeth wear away, and second, in order that the swinging teeth may be more easily cut in the periphery of this light casting than they would be, were they a part of the heavy central steel casting.
- 65 The rear end of the revolving frame consists of a large casting attached to the central portion of the revolving frame in place of the usually large number of small castings fastened together. The same is true of the revolving frame or roller beam. Thus there are two large castings fastened together to form the swinging platform or frame, one of them supporting the boiler 70 and associated parts, the other supporting the jib or boom and associated parts together with the operating and controlling mechanisms, and by this arrangement and by the arrangement I have shown of reinforcing, stiffening and supporting members, the parts are all tied together reinforced and supported with a minimum of complication, and by my arrangement I am also enabled to provide a free and unobstructed 75 passage for the engineer from side to side of the machine, thus enabling him to do his work with a minimum of difficulty, protecting him against danger of being caught at one side of the machine when his presence
- 80 85 90 95 100 105 110

The invention is illustrated more or less diagrammatically in the accompanying drawings, wherein—

Figure 1 shows a plan view of a car body embodying my invention;

Fig. 2 is a side elevation of the car body;

Fig. 3 is a side elevation in part section of the revolving frame;

Fig. 4 is a plan view of the revolving frame.

Like parts are indicated by like characters in all the figures.

A is a heavy rigid center casting. It is as shown preferably rectangular in shape. 15 To it are adapted to be bolted, riveted or otherwise attached the car side frames A¹, A¹. These side frames are tied together by cross girders A², A² arranged preferably in two pairs at either end of the car, that is, 20 with one girder at the extreme end and one between such extreme end girder and the center frame. The inner cross girders are provided with center bearings A³ adapted to rest upon and thus support the car body 25 on the wheel trucks A⁴. Downwardly depending from the ends of the car outside the wheel trucks beneath the end cross girders are the frames A⁵, A⁵ in which are slidably mounted the outrigger beams A⁶, 30 A⁶ resting on the rollers A⁷, A⁷. These beams are adapted to move in opposite directions and extend outwardly away from the sides of the car so as to bolster the car when it is being used as a stationary crane 35 and prevent its tipping over when a load is lifted from a position outside the track line. A⁸ is an ordinary type of draw bar slidable in the usual friction draft gear A⁹ whereby the car may be coupled into a 40 train in the usual way.

The above describes in general terms the arrangement of the car body itself. It will be understood that the car body is merely a vehicle for the carrying of the crane parts 45 and that it differs from the ordinary type of car body in that it is more rigid and ponderous and in that it is built up about a single rigid casting which carries the working and hoisting parts and which co- 50 operates with the other parts of the car body to give a stiff and rigid structure. It will further be understood that the side frames are fabricated and then attached to the casting, the cross beam being then built 55 into the structure. This leads obviously to a simple and convenient method of manufacture and results in a more durable structure and a less expensive one in proportion to its weight than would otherwise be the 60 case.

Center casting.

The center casting A while it is generally rectangular so far as its outside shape and 65 dimensions are concerned comprises a cen-

trally disposed circular portion B which is supported by integral ribs B¹, B² extending radially from it to the outside rectangular portion of the frame. This circular portion is provided with flanges B³, B⁴ and these flanges have opposed roller tracks B⁵, B⁶ spaced slightly from the outside wall so as to easily guide without interference from the side wall the rollers which support the swinging platform which will subsequently be described. The lower track B⁵ only assists in carrying the weight of the mechanism itself and does not ever come into play when the crane is carrying a load, therefore. The flange B³ which is on the lower side of the casting is made relatively light as indicated. The track B⁶, however, assists in counterbalancing the weight of the load and the flange B⁴ which carries it is a rigid and heavy part of the casting. 75 B⁷ is a separate circular ring adapted to be bolted or riveted or otherwise attached to the upper side of the flange B⁴. It carries an inclined roller track B⁸ and has cut in its periphery the gear teeth B⁹ of the 80 swinging gear.

Depending downwardly from the casting A beneath the central portion of the ring B is a rectangular frame C tied to the casting at its corners and at its sides by means 85 of the webs C¹, C¹. Sliding in the cradle thus formed is an outrigger bar C² which is adapted to be manipulated by means not here shown and which since it forms no part of the present invention I shall not 90 further discuss. Extending upwardly above this frame C but terminating below the body of the casting A is a frame C³ made up of a series of integral webs which supports a central cup C⁴. C⁵ is a central 95 vertically disposed aperture through the cup C⁴ and its supporting parts which is provided for the purpose of furnishing a bearing for the connecting shaft C⁶ which transmits the motive power from the engine 100 to the driving wheels. This, however, forms no part of my present invention and is described.

Revolving frame.

D is a roller frame casting. It is provided at its front end with two trucks D¹ in each of which are rotatably mounted rollers D² which rest upon and travel along the track B⁸. These two pairs of rollers are 110 located one on either side of the axial line of the roller frame casting. The forward end of this casting is provided with a sleeve D³ which carries a shaft D⁴ adapted to be driven by any suitable means not here 115 shown and which carries at its lower extremity the driving pinion D⁵ in mesh with the gear B⁹ whereby the revolving frame may be rotated in the usual manner at the will of the operator. D⁶, D⁶ are a pair of 120 125 130 135

brackets downwardly extending from the rear side of the roller frame casting and these brackets carry rollers D⁷ which travel between the tracks B⁵, B⁶, the parts being so arranged that when there is no load on the jib D⁸ the load is carried by the rollers D² and D⁷ on the tracks B⁵, B⁸, but when the jib carries a load the roller frame is tilted up through, of course, a very short distance until the rollers D⁷ engage the tracks B⁶. By this arrangement no king bolt is needed at the center to hold the apparatus down on the tracks. D⁹ is a sleeve which penetrates the cup C⁴ and is in rotatable engagement therewith. It has for its purpose to assist in centering the roller frame or beam on this circular track though, of course, the inclined track and roller contact lines do assist in this function.

E is a large casting forming the boiler platform. It is attached to the rear end of the roller frame D by means of pins E¹ and takes the form of a large plate girder. E², E³ are side frames erected upon the roller beam D and it is on these side frames that the jib D⁸ is pivoted by means of a pivot pin E³. These side frames extend upwardly a considerable distance above the frame D and platform E. E⁴ are links pivoted at one end on the upper apex of the side frames E² and extend rearwardly therefrom. These links are tension links. E⁵ are compression links pivoted on the lugs E⁶ on the rear edges of the side frames E² and in pivotal engagement with the links E⁴ adjacent their outer ends. E⁷ are stirrup links pivoted at the outer ends of the links E⁴ and pivoted on the platform E at a point far removed from the pins E¹ and so disposed with respect to the boiler E⁸ that there is a free passage across the platform between the boiler and the link E⁷ on the one hand and the side frame E² and link E⁵ on the other. E⁸, E⁹ are stay members riveted to the links E⁴ at one end to the top of the boiler E⁸ at the other to steady the boiler on the platform. It will be understood that the operating mechanism is located between the side frames E². The semi-cylindrical notches E¹⁰, E¹¹ are provided for the purpose of supporting the bearings for some of the operating machinery and the same is true of the bearing sleeve E¹². The remainder of the mechanism will be supported inside between the frames by means not here illustrated. It will be understood of course, that I have only partially illustrated the actual locomotive crane structure but this is justified by the fact that the parts which I have shown form the essential features of my invention and their arrangement and operation would be obscured rather than clarified by the introduction of all operating, driving and controlling parts. I wish,

therefore, that my drawings be regarded as in a sense diagrammatic.

I claim:—

1. A crane carbody comprising a base plate which supports the lifting mechanism and the load, two side girders which support the base plate upon the trucks and the end jack arms, and shear connections whereby the base plate transfers its load to the side girders, said shear connections being widely separated, thus reducing the bending moment upon the side girders and causing the base plate to carry said bending moment in the region between the shear connections.

2. A crane carbody comprising an integral base plate which supports the lifting mechanism and the load, two side girders which receive the load from said base plate, two transverse end girders which carry the inner ends of a system of end jack arms, two transverse intermediate girders which support the carbody upon two trucks and a central jack arm box extending substantially from one side girder to the other.

3. In a crane, a carbody and a central jack arm construction comprising an integral base plate which carries the lifting mechanism and the load, two side girders attached to the base plate, a transverse central jack arm box suspended at its two ends from the side girders by the adjacent parts of the base plate and a central jack arm which reacts downward upon the ground, upward on the undersurface of one of the side girders and downward at a point near the center of the jack arm box.

4. In a revolving crane, an integral base plate which supports the lifting mechanism and the load, the interior periphery being of circular form to furnish and support flanges for engagement with the rollers said flanges forming a circular track about the interior periphery and the exterior periphery having two substantially parallel sides to engage supporting girders.

5. In a revolving crane, an integral base plate which supports the lifting mechanism on the load and flanges formed thereupon for engaging the rollers which support the revolving mechanism, said flanges forming a circular track about the interior periphery of the base plate.

6. In a revolving crane, a base plate which supports the lifting mechanism and the load, flanges formed therein for engaging the rear rollers of the revolving frame and their roller tread upon the upper surface of the base plate for supporting the forward rollers of the revolving frame.

7. In a revolving crane, a base plate which supports the revolving mechanism and the load, flanges formed upon the attached interior circular web thereof for engaging the rear rollers of the revolving frame, a

- roller path formed upon the upper surface thereof for supporting the forward rollers of the revolving frame and a circular ring of gear teeth for engaging the swinging pinion.
- 5 8. In a revolving crane, an integrally cast base plate comprising flanges which engage the rear rollers of the revolving frame and a separable roller path which engages the forward rollers of the revolving frame and 10 which also embodies a swinging rack.
9. In a revolving crane, an integral cast base plate embodying a set of flanges for engaging both the rear and the forward rollers of the revolving frame and a separable circular swinging rack attached to said base 15 plate.
10. In a revolving crane, a base plate which supports the revolving frame and the load and which carries one flange located adjacent to and above the rear revolving frame 20 rollers, another flange adjacent to and below the rear revolving frame rollers, whereby their upward or downward reactions are imparted to the base plate through the same 25 rollers.
11. In a revolving crane, an integral cast base plate comprising a circular ring portion having top and bottom flanges and adapted to resist roller loads, two parallel 30 side girder portions for attachment to side car girders and two transverse torsional portions connecting the said girder portions.
12. In a revolving crane, an integral cast base plate comprising a circular ring portion 35 having top and bottom flanges and adapted to resist roller loads, two parallel side girder portions for attachment to side car girders and a transverse torsional portion connecting the side girder portion.
- 40 13. In a revolving crane, a base plate structure comprising a circular ring member having top and bottom flanges and adapted to resist roller loads, two parallel side girder members for attachment to side
- car and girders and two transverse torsional members connecting the side girder portions. 45
14. In a revolving crane, a cast base plate comprising a circular ring portion having top and bottom flanges adapted to resist the reactions of a part of the rollers and a separate ring portion attached to the upper surface of the main base plate and comprising a roller path for the remaining rollers. 50
15. In a revolving crane, a cast base plate comprising a circular ring portion having top and bottom flanges adapted to resist the reactions of a part of the rollers and a separate ring portion attached to the upper surface of the main base plate and comprising a roller path for the remaining rollers and a toothed swinging rack. 55
16. In a crane, a car body and a central jack arm construction comprising an integral base plate which carries the lifting mechanism and the load, two side girders attached to the base plate, a transverse central jack arm box suspended at its two ends from the side girders by the adjacent parts of the base plate, and depending beneath the bottoms of the side girders, and a central jack arm which reacts downward upon the ground, upward on the under surface of one of the side girders and downward at a point near the center of the jack arm box. 65
17. A crane car body comprising an integral base plate which supports the lifting mechanism and the load, side girders and transverse girders, and means for supporting them, and a central jack arm box supported by the side girders and depending beneath them. 70
- In testimony whereof, I affix my signature in the presence of two witnesses this 28th day of February, 1917.
